Patented June 9, 1914.

Fig. 2. shows a truss structure with vertical posts 4 at the corners and a horizontal beam 11 across the middle. Diagonal members 10 are positioned from the top corners to the midpoint of the horizontal beam. A vertical dashed line 16 is shown on the right side, and a horizontal dashed line 13 is shown at the top right corner. A label 17 is at the bottom center.

UNITED STATES PATENT OFFICE.

ALFRED C. WEISSMANN, OF NEW YORK, N. Y.

BOOKBINDER'S TRUCK.

1,099,226.

Specification of Letters Patent.

Patented June 9, 1914.

Application filed October 21, 1913. Serial No. 796,421.

To all whom it may concern:

Be it known that I, ALFRED C. WEISSMANN, a citizen of the United States, and a resident of the city of New York, Forest Hill, 5 borough of Queens, in the county of Queens and State of New York, have invented certain new and useful Improvements in Bookbinders' Trucks, of which the following is a specification.

10 This invention relates to certain new and useful improvements in book binders' trucks.

The object of my invention is to provide a new and improved book binder's truck which is simple in construction, strong, durable, easily operated and which is adapted to hold the brass bound press boards or other press boards to the tension rods with their tightening nuts and also the top and bottom boards, when not in actual use for 20 pressing books, in such a manner that these parts will not be lost or damaged or injured and are always in the most convenient position for immediate use and which truck has a further advantage that it can be easily 25 shifted with or without the load thereon and occupies less space both when in use and out of use than the trucks used heretofore.

In the accompanying drawings in which like letters of reference indicate like parts 30 in all the figures:—Figure 1 is a side view of my improved book binder's truck showing the method of carrying the presser boards, the top and bottom boards and the tension rods when not in use. Fig. 2 is a rear end 35 view of the truck. Fig. 3 is a side view of the tension rods. Fig. 4 is an enlarged detail plan view of one of the standards. Fig. 5 is a detail plan view of one rear corner of the truck platform. Fig. 6 is a plan 40 view of one end of the underside of the bottom board for the pile of presser boards and books between them. Fig. 7 is a plan view of one end of the top board of the pile.

The truck is constructed with a platform 45 1 or base to the under side of which rollers 2 of any approved construction are secured and mounted. At the two rear corners of the platform 1 a rectangular piece is cut out to form a rectangular recess 3 for a purpose 50 that will be set forth hereinafter. An angle iron upright 4, fitting snugly on each corner 5 of the platform 1 is bent over rectangularly beneath the platform 1 of the truck and is secured to said under side in such

manner that the standard 4 extends upward. 55 It is secured and braced by an inclined brace 6 attached to the upright 4 and to the side edge of the base board 1 which braces 6 thus form sides for the presser boards 7 which are placed on edge on the platform 1 as 60 shown in Fig. 1. A metal strap 8 is secured to the rear edge of the platform 1 and its ends are bent over rectangularly as shown at 9 and secured to the sides of the platform over the side flanges of the uprights 4 so as 65 to form an outer wall for the recess 3. Inclined struts or braces 10 are secured at their upper ends to the uprights 4 and at their lower ends to the rear edge of the platform 1, said struts or braces crossing each other 70 to form a back for the truck. A metal band or strap 11 having its ends bent rectangularly as at 12 has these ends 12 riveted to the upright 4 about $\frac{1}{2}$, more or less, of the height of said uprights so that this band 11 75 will be a certain predetermined distance from the cross struts 10 for a purpose that will be set forth hereinafter. To the upper end of each upright 4 a curved metal arm 13 is riveted by means of a flange 14 of said 80 arm, which flange rests against the outer surface of the side flange of the upright, a rivet being passed through the flange 14 of the arm 13 and the flange of the upright as shown in Fig. 4, which curved arm thus 85 forms a socket adapted to receive the bottom neck 15 of the winged nut 16 screwed on the upper threaded end of the tension rod 17 which at its lower end is provided with a cross piece 18. 90

The bottom board 19 for the pile is provided at each end with a socket plate 20 having a slot 21 for introducing the rod 17 so that the lower cross piece 18 of the rod can rest in a socket formed in the under side of 95 the plate 20. The top board 22 for the pile of presser boards is provided in each end with a recess 23 formed in an end part of the board 22 and in a plate 24 secured at said end, on which plate 24 the bottom of the 100 neck 15 of a nut 16 can rest. The bottom board 19, the top board 22, the tension rod 17 and its winged nut 16 are of the same construction as those used heretofore. The bottom board 19 is placed on the press platform 105 and then a series of brass bound presser boards or other presser boards, such as are generally used in book binderies and books

22

between said boards are piled upon the bottom board 19 until the desired quantity is in place, whereupon the top board 22 of the pile is placed on top of the pile and then by 5 means of an ordinary screw press or hydraulic press the presser boards and books between them are pressed together in the conventional manner. Then the cross pieces 18 of the two tension rods 17 are engaged with 10 the socket plates 20 in the under side of the bottom board 19, the top board 22 is placed upon the pile and the upper ends of the rods 17 passed into the notches 23 and the winged nuts 16 are screwed down until they rest 15 firmly upon the top board 22 so as to hold and keep the books under pressure and to prevent them from expanding when the pile is taken from the press, all as has been set forth heretofore. The follower or presser 20 plate of the press is then raised and the entire pile of books and presser boards held between the bottom board 19 and the top board 22 by the rods 17 and nuts 16, is pulled off the press and placed upon the platform of 25 the truck and on said truck is carried to a space for storage and there the entire pile, while still held together by the rods 17 is discharged from the truck so that the books remain under pressure between the presser 30 boards any desired length of time. The truck can easily be handled and shifted by grasping the uprights or standards 4 as handles. After the books have been thus held under pressure for the desired length of 35 time, the nuts 16 are loosened, the rods 17 disengaged and the several presser plates and books are lifted off. The presser plates 7 are placed on edge on the truck platform, their inner ends resting against the cross 40 struts 10 and the side struts 6 holding these presser plates on edge and preventing them from tilting. The bottom board 19 is placed upon the top edges of the several presser boards resting on edge on the truck and the 45 top board 22 is placed, on edge upon that rear part of the platform projecting rearward beyond the uprights 4 and is held in place by being passed in between the rear cross band 11 and the struts 10. The upper 50 ends of the rods 17 are placed into the sockets formed by the curved arms 13 on the uprights 4 and the lower ends of these rods are passed downward through the recess 3 and then the rods are released or lowered so that 55 the necks 15 on the winged nuts 16 pass into the sockets formed by the curved arms 13. The rods 17 are thus always held in the proper place on the truck and cannot be lost or damaged and are never out of place, their 60 lower ends being in the recesses 3 and the rods are thus within reach of the operator when he wishes to remove the pile of books from the press and hold them together before removal. The presser boards 7 which 65 are usually bound on the edges with metal or

fiber or other suitable strips which project beyond the faces of the boards, are held in convenient position and the projecting edges of the strips are not apt to be damaged as they would be if the boards were placed flat, 70 one upon the other. If books are to be placed into a press it is only necessary to move the truck with the presser boards, tension rods and top and bottom boards thereon in the manner shown, to the press, then 75 place the bottom board upon the base of the press and then alternately a layer of books and then a presser board, one upon the other. Then remove the top board from its pocket or holder on the truck and place it on top 80 of the pile and then remove the tension rods 17 from the uprights 4 and engage them with the top and bottom boards of the pile and tighten the nuts and so on.

Having described my invention what I 85 claim as new and desire to secure by Letters Patent is:—

1. In a book binder's truck, the combination with a truck platform, of standards on one end of the same and sockets formed on 90 the upper ends of the standards for suspending detachable tie rods, substantially as set forth.

2. In a book binder's truck, the combination with a truck platform, of standards on 95 one end of the same and sockets formed on the upper ends of the standards for suspending detachable tie rods and braces extending from the standards to the side edges of the platform and forming the sides of the 100 upper part of the truck, substantially as set forth.

3. In a book binder's truck, the combination with a truck platform having recesses at the rear corners, of a band attached to the 105 rear end of the platform and closing the sides of said recess, uprights attached to the rear corners formed by the sides of the platform and an edge of one of said recesses and sockets formed on the upper ends of 110 said uprights for receiving part of the tie rod, substantially as set forth.

4. In a book binder's truck, the combination with a truck platform, of uprights secured to the rear corners, sockets on the 115 upper ends of said uprights for receiving the nuts on tie rods, a cross piece having angular ends and uniting the uprights above their lower ends and forming a pocket for receiving and holding a board on edge 120 on the rear end of the platform, substantially as set forth.

5. In a book binder's truck, the combination with a truck platform, of an upright on each rear corner, inclined braces attached to the rear part of the platform and to the 125 said uprights, a cross bar attached at its ends to the uprights some distance above the lower ends of said uprights, said cross bar being bent at its ends so that its major 130

portion is located horizontally a short distance from the outer side of the inclined braces to form a pocket for the board placed on edge on the rear end of the platform and held between said inclined braces and the said cross bar, substantially as set forth.

6. In a book binder's truck, the combination with a truck platform having recesses at each rear corner, an upright secured to 10 each rear corner formed by the side edge of the platform and the adjacent edge of one of said recesses, a metal strap secured at the rear end of the platform and forming the outer closures for said recesses, inclined 15 braces uniting the uprights to the rear end of the platform and a bar attached to the uprights and extending across the inclined braces to form a pocket above the rear end

of the truck and between said bar and the cross pieces, substantially as set forth. 20

7. In a book binder's truck, the combination with a platform, of uprights on the rear corners of the same, sockets on the upper ends of the uprights, pockets formed at the rear corners of the platform for receiving 25 the lower ends of rods, the upper ends of which are suspended in the sockets on the upper ends of the uprights, substantially as set forth.

Signed at New York city in the county 30 of New York and State of New York this 16th day of October A. D. 1913.

ALFRED C. WESSMANN.
